UNITED STATES PATENT OFFICE.

HORACE L. ROBERTS, OF NEW YORK, N. Y.

THREAD-STITCHING MACHINE FOR PAMPHLETS AND SIMILAR ARTICLES.

1,001,308.

Specification of Letters Patent. Patented Aug. 22, 1911.

Application filed June 8, 1910. Serial No. 565,735.

To all whom it may concern:

Be it known that I, HORACE L. ROBERTS, a citizen of the United States, residing at New York city, Brooklyn, county of Kings, 5 State of New York, have invented new and useful Improvements in Thread-Stitching Machines for Pamphlets and Similar Articles, of which the following is a specification.

10 This invention relates to a thread stitching machine for uniting the sheets or signatures of pamphlets, books and similar articles, such, for instance, as described in Patent No. 944,051 granted to me on December 21, 1909.

The invention comprises more particularly novel and effective means for properly guiding the thread while the same is drawn through the previously formed needle holes 20 of the pamphlet, so that any undue widening of said holes and a tearing of the pamphlet is prevented.

The invention also comprises novel means for properly opening the central loop of the 25 stitch forming thread, so that the loopers carrying the thread ends may readily pass through the same.

In the accompanying drawing: Figure 1 is a sectional front view of part of a thread 30 stitching machine embodying my invention, Fig. 2 a plan thereof, with the table and presser foot omitted, Fig. 3 a bottom view of part of the means for actuating the loop opener, Fig. 4 an enlarged vertical section 35 on line 4—4, Fig. 2, showing the table and presser foot in position, Fig. 5 a similar section on line 5—5, Fig. 2, Fig. 6 a sectional rear view of the presser foot, Fig. 7 a plan of the presser foot and its guide, Fig. 8 a 40 detail of the movable presser foot plate, Fig. 9 a section on line 9—9, Fig. 8 and Fig. 10 a detail showing the thread partly drawn through the pamphlet.

The machine comprises essentially a table 45 adapted for the support of the pamphlet to be stitched; a presser foot which holds the pamphlet to the table; three needles which first pierce said pamphlet from the outside toward the inside and then draw the thread 50 through the needle holes in such a manner that the central needle forms an outwardly extending thread loop; an opener which spreads said loop; and a pair of loopers which pass through the opened loop, draw 55 the thread-ends therethrough and finally close the loop upon said ends.

The means for operating the presser foot, needles and loopers are embodied in the patent above referred to, while the construction of the novel presser foot and of the 60 loop opener and its operating mechanism are as follows: In a recessed guide 15 which constitutes part of the machine frame, is mounted a vertically reciprocative shank 16. This shank is recessed for the reception of a 65 plunger 17 while a suitable face plate 18 holds shank 16 and plunger 17 to guide 15. Into plunger 17 is tapped a pin 19, the enlarged stem 20 of which passes through slots 21, 22 of shank 16 and guide 15 respectively. At its outer end, pin 19 carries an antifriction roller 23, which engages the groove 24 of a segmental cam 25, said cam and its actuating mechanism being in all respects identical with the cam 58 and the 70 parts coöperating therewith as described in the above cited patent. From shank 16 projects forward and downward a slotted foot 26, the lower longitudinal edge 27 of which is arranged vertically above the furrow of 80 table 28 supporting the pamphlet 29. The lower rear side of foot 26 is recessed as at 30 for the reception of a slide 31, suitable guides 32 confining said slide within said recess. Along its lower edge, slide 31 is 85 provided with three slightly up-turned prongs 33, having semicircular notches 34 which permit the passage of the stitch-forming needles 35. Near its upper end, slide 31 has a longitudinal slot 31^a which is permanently engaged by a tongue 36 projecting rearward and downward from plunger 17, so that tongue 36 extends at right angles to slide 31. 90

Fig. 4 shows the presser foot in the position it occupies while the thread is drawn through the pamphlet, the means for supplying and stretching the thread above and along the table furrow being fully described in the above cited patent. It will be seen 95 that in this position, slide 31 is so forced into the fold of the pamphlet, that prongs 33 extend forward beyond said fold. Thus when needles 35 draw the thread through the pamphlet, the thread will not 100 slide along the pamphlet-fold but will be temporarily supported by prongs 33 (Fig. 10) so that any undue widening of the needle holes and a consequent tearing of the pamphlet fold is effectively prevented. After the 105 thread has been drawn almost entirely through the pamphlet and previous to its 110

being finally locked, plunger 17 is raised by cam 25, while foot 26 will remain in its lowered position owing to its weight. During this upward movement of plunger 17, tongue 36 will raise slide 31 along foot 26 thereby withdrawing prongs 33 from the pamphlet fold, so that the stitch may be locked by the loopers. The withdrawal of slide 31 will continue until shank 20 impinges against the upper edge of slot 21 thereby taking along shank 16 and thus raising foot 26 to release the stitched pamphlet. After the next pamphlet has been placed upon table 28, shank 16 and plunger 17 descend in unison until the unrecessed outer sections 37 of foot 26 find a bearing upon the pamphlet, so that the continued descent of pin 19 will, by tongue 36 cause a corresponding advance of slide 31 to project its prongs over the pamphlet fold, whereupon the operation described is repeated.

The means for opening the downwardly extending central thread loop comprise a pair of superposed slides 38, 39, having upward turned front sections 40, 41 that carry tapering beaks 42, 43 respectively. Slides 38, 39 are mounted in a corresponding guide way of a carriage 44 engaging a dovetailed stationary rail 45, a disengagement of the slides from the carriage being prevented by cross pieces 46. The coöperation of the parts is such that while carriage 44 travels along the pamphlet-fold, slides 38, 39 travel at right angles thereto. Into slides 38, 39 are tapped a pair of screws 47 carrying antifriction rollers 48 which constitute abutments and engage opposite edges of a longitudinally reciprocative cam rail 49, a spring 50 suspended between slides 38, 39 tending to draw rollers 48 against said rail. Rail 49 is secured to the slide 51 of one of the loopers 52 and thus participates in the reciprocative movement of the latter, while any disengagement of the rail from the carriage is prevented by a cross piece 53. Near its free end, rail 49 is provided with a pair of recesses 54 that form a head 55 at the end of the rail. When rollers 48 engage recesses 54, beaks 42, 43 are closed (Fig. 5) while when the rollers engage the unmutilated section of rail 49, the beaks are opened, as will be readily understood. Besides operating the loop opening beaks, rail 49 has the addi-

tional function of reciprocating carriage 44 so as to project the beaks into thread loop 56, and to withdraw them therefrom. For this purpose the tension of spring 50 should be such that when rollers 48 are engaged by the inclined sections 57 of rail 49, they will first be taken along by said rail thereby shifting carriage 44 to the left until the latter engages an adjustable stop 58 secured to the bottom of rail 45 by a screw 59 passing through a corresponding slot 60 of said stop. During this travel of carriage 44 the closed beaks 42, 43 will enter loop 56, while during the continued advance of rail 49, the rollers 48 will ride along sections 57, thereby opening beaks 42, 43 and spreading loop 56. During the subsequent return movement of rail 45, the rollers 48 will first enter recesses 54 to close beaks 42, 43 whereupon said rollers are engaged by head 55 thus returning carriage 44 into its original position.

I claim:

1. In a stitching machine, a needle adapted to form a thread-loop, a carriage, a pair of slides mounted therein, beaks on said slides that are adapted to enter said loop, and means for reciprocating the carriage and for simultaneously reciprocating the slides in opposite directions and at right angles to the direction of reciprocation of the carriage.

2. In a stitching machine, a carriage, a pair of spring-influenced slides mounted therein, loop-opening beaks on said slides, and a recessed rail adapted to reciprocate the carriage and to open the beaks.

3. In a stitching machine, a carriage, a stop adapted to be engaged thereby, a pair of spring-influenced slides mounted in the carriage, loop-opening beaks and abutments on said slides, and a recessed reciprocative rail engaging said abutments.

4. In a stitching machine, a carriage, an adjustable stop adapted to be engaged thereby, a pair of spring-influenced slides mounted in the carriage, loop-opening beaks and abutments on said slides, and a recessed headed rail reciprocatively mounted between said abutments.
